UNITED STATES PATENT OFFICE.

CHESTER H. BEACH, OF RACINE, WISCONSIN, ASSIGNOR TO WISCONSIN ELECTRIC COMPANY, OF RACINE, WISCONSIN, A CORPORATION OF WISCONSIN.

SANITARY AGITATOR FOR DRINK-MIXERS.

1,201,920.

Specification of Letters Patent. Patented Oct. 17, 1916.

Application filed June 21, 1915. Serial No. 35,349.

To all whom it may concern:

Be it known that I, CHESTER H. BEACH, citizen of the United States, residing at Racine, in the county of Racine and State of Wisconsin, have invented a certain new and useful Improvement in Sanitary Agitators for Drink-Mixers, of which the following is a full, clear, concise, and exact description.

10 My invention relates to improvements in power driven agitating devices such as are used for example for mixing or stirring beverages or the like. In prior devices of this general character, the agitator rod is rotated by an electric motor, and constitutes in effect, a permanent part of the armature shaft. The agitator is raised and lowered either by raising and lowering the entire motor, or by sliding the agitator rod 15 through the armature shaft, which, for this purpose, is made tubular. In either case, the same agitator rod is used in stirring the different liquids in all the various receptacles in which it is immersed successively, 20 which feature has given rise to objections from a sanitary standpoint.

The general object of the present invention is to provide an agitator which permits of more sanitary methods in the use thereof.

25 A contributory object is to provide an agitator rod, the lower part of which is readily removable from the upper part whereby said lower part may be readily detached and rinsed after each operation, or, 30 whereby it may be thrown away and a new one substituted for each operation.

Another object of the invention is to provide an agitator head or main agitating element which may be operated at the very bottom of the receptacle thus insuring a 35 complete circulation of the liquid and consequently thorough mixing.

A further object is to provide an agitator rod in two telescopic sections which latter are relatively adjustable to meet varying requirements.

40 An additional object is to provide an agitator rod with means for insuring against accidental withdrawal thereof through the motor shaft, but which may be forcibly withdrawn if desired.

45 Other objects and advantages will appear from the following description without specific enumeration thereof.

50 In the accompanying drawings, I have

shown one embodiment of my invention in conjunction with a motor having a tubular armature shaft in which the upper part of the agitator rod is slidable. The invention may be embodied in other forms, however, 60 and may be used with motors which are moved bodily up and down, and, of course, with other types of driving means.

Figure 1 is a side elevation of the form of device above mentioned. Fig. 2 is a section 65 on the line 2-2 of Fig. 1. Fig. 3 is an enlarged elevation of the lower part of the agitator rod. Fig. 4 is an enlarged elevation of the upper part thereof. Fig. 5 is an enlarged section on the line 5-5 of Fig. 3. 70

The general organization consists preferably of a suitable base 1 having a standard 2 thereon carrying an electric motor 3 near the upper end thereof. Said motor is provided with a hollow armature shaft 4 which 75 is supported by an enlargement or head 5 on the upper end thereof, forming a shoulder, said head having a plurality of recesses 6 therein, hereinafter referred to. Upward movement of the armature shaft is prevented by a cap 7.

The agitator rod is made in two sections as previously stated. For convenience, the upper section 8 may be called the spindle or driving rod and the lower removable section 9 may be called the agitating element. The spindle 8 fits within the hollow armature shaft 4 and is slidable therein. To provide a driving connection between said armature shaft and the spindle freely rotatable therein, I provide one or more downwardly extending projections or arms 10 at the upper end of the spindle adjacent to the knob or handle 11. These projections drop readily into the recesses 6 previously mentioned and insure a positive driving connection between the armature shaft and said spindle. Whenever the latter is raised slightly, the parts are uncoupled whereby the spindle may be held against rotation by means of the knob 11, even though the motor should continue to run. The lower end of said spindle is slotted providing two or more resilient prongs 12 which are sprung apart somewhat and are provided with heads 13 to insure friction between said spindle and the agitating element 9 when the latter is fitted over said spindle. Shoulders 14 are also provided which engage the lower end of the hollow armature shaft when the 100

105

110

spindle is raised thereby preventing the spindle from being accidentally lifted entirely out of said hollow shaft. Whenever it is necessary for any reason, to remove 5 said spindle, however, said removal may be readily accomplished by forcing together the spread apart lower ends thereof.

The removable section 9 is provided with a finger piece 15 at the upper ends thereof, 10 which latter provides a flaring opening to guide the spindle, and is made preferably of insulating material, for example, hard rubber. At the lower end thereof, an enlargement or head 16 is provided, which, 15 when rotating, acts as an agitator and throws the liquid outwardly by centrifugal force, thereby insuring circulation thereof. Said head, which is preferably square, is provided with a tapering extension 17 20 adapted to rest against the bottom of the tumbler or other receptacle 18. This extension forms a pivotal support for the removable section, which latter is at least as long as the depth of the liquid to keep the 25 finger piece above the level of said liquid. The head 16, being located near the bottom of the receptacle, the resulting circulation is very complete.

In using the device, the spindle 8 is raised 30 so as to permit the tumbler 18 to be placed beneath it, the section 9 having previously been dropped into the tumbler or held suspended in it by the finger piece. The spindle is then lowered into said section thereby 35 frictionally engaging the latter, whereby the two rotate as one. After the stirring operation is completed, the spindle is raised, whereupon said section may be lifted from the tumbler and cleaned before being used 40 again. The device is thus very sanitary as it is an easier operation to clean said section after removing it from the spindle than to rinse and clean the lower end of the spindle where the agitator rod is a one-piece 45 construction. The sanitary feature may be further carried out by making said removable sections of some inexpensive material whereby they may be thrown away after using them once.

50 Having thus described my invention what I claim as new and desire to secure by Letters Patent of the United States is:

1. The combination with a suitable support, of an electric motor mounted thereon with its shaft vertical, an agitator constituting a separate element readily detachable from said shaft but arranged to be rotated thereby, and means for raising and lowering said shaft to facilitate attachment and removal of said agitator.

2. In an agitator, the combination with a standard having means for holding a tumbler, of an electric motor supported thereby having a vertical armature shaft, an agitator rod associated with said shaft, said rod

being made in two detachable sections, the lower of which is arranged to extend to the lower part of said tumbler and means for elevating the upper of said sections, whereby the lower one may be removed after each 70 operation.

3. In an agitator, the combination with an electric motor having a vertically disposed tubular armature shaft, of a longitudinally movable vertical agitator rod loosely 75 inclosed by said shaft and provided near its upper end with means whereby the rod may be coupled to said armature shaft, the lower end of said agitator rod being detachable from the upper end thereof whereby it may be readily removed therefrom and cleaned.

4. In an agitator, the combination with an electric motor having a tubular armature shaft with a spindle passing loosely there- 85 through, an extension having telescopic engagement with the lower part of said spindle and means co-operating with said spindle and with said tubular armature shaft to positively drive said spindle.

5. In an agitator, the combination with an electric motor mounted above a suitable base, a tubular armature shaft therefor at a height sufficient to permit a liquid receptacle to be placed on said base beneath said 95 shaft, a slideable spindle carried by said armature shaft and arranged to be lifted until its lower end clears said receptacle, and an agitator element substantially as long as said receptacle arranged to rest on the bottom thereof and be connected to said spindle whereby it may be driven thereby when 100 said spindle is lowered.

6. An agitator rod comprising a spindle having an extension in telescopic engagement therewith, the lower end of said spindle being slotted and spread to insure friction at that portion thereof, whereby a driving connection is provided regardless of the extent to which said extension is telescoped 110 over said spindle.

7. An agitator rod comprising a spindle having a knob at the upper end and having an enlarged yielding portion at the lower end thereof, a tubular extension arranged 115 to fit over said spindle and have frictional engagement with said enlarged end, said extension having an agitator head at the lower end thereof and having a finger grip at the upper end thereof.

8. A sanitary agitator rod for beverages comprising an agitator element of a length substantially equal to the depth of an average tumbler whereby it may rest on the bottom of said tumbler and project above 125 the surface of the liquid, and means arranged to be lowered into telescopic engagement with said extension to rotate it, and arranged to be raised out of engagement therewith in removing said tumbler.

9. A hollow agitator rod having a flaring finger piece at its upper end to facilitate making a telescopic driving connection and having a square agitator head at its lower end provided with a tapering extension constituting a pivotal support.
10. In an agitator, the combination with an electric motor, a tubular armature shaft therefor having an enlarged head with a recess therein, a cap for said head holding said armature shaft in place, a spindle pass-

ing loosely through said armature shaft, a projection at the upper end thereof for engaging said recess to provide a driving connection and a yielding enlargement at the lower end of said spindle for preventing such spindle from being lifted out of the armature shaft unless said end is compressed.

In witness whereof, I hereunto subscribe my name this 17th day of June, A. D. 1915.

CHESTER H. BEACH.
